INDICATOR DIALS**Maria Panerai and Giuseppe Panerai, Florence, Italy****Application May 6, 1958, Serial No. 733,352****Claims priority, application Italy May 14, 1957****6 Claims. (Cl. 116—133)**

The present invention relates to an improvement in the dials of indicators, where a pointer movable on a disc supplies an information in accordance with a number of information elements carried by said disc.

For special applications which can readily appear to the skilled persons in the art of the remote transmission of data, the problem occurs according to which the actual positions of the information elements carried by the dial no more correspond to their exact locations, or said elements have to be peripherally moved at intervals which are not uniform and which may also vary through a given time period, for instance depending upon different adjustments of the transmitting element which may drive the movement of a pointer with respect to the dial, or of the dial with respect to a stationary mark or reference.

Obviously, in such a case, a dial wherein the information carried thereby are rigidly fixed in constant positions with respect to each other, does not lend itself to the solution of the technical problem.

This invention aims to find the solution allowing these difficulties to be overcome, rendering adjustable the positions of the information elements with respect to each other, and obviously also of all of the elements with respect to the dial.

This possibility is reached by furnishing the dial with clamping means for inserts on which are marked the information elements or indications, said clamping means being capable of allowing little relative adjusting movements of the aforesaid elements.

Generally speaking, the dial is provided with a recess apt to receive said information elements and with the means for retaining said elements in locations radially equispaced or not. Of course the recess has the only functional purposes of providing a flat surface on the dial, and in fact should not be necessary to have all of the information elements lying in a single plane, with no discontinuity, said elements can also be applied so as to individually project from a single flat surface forming the support element of the dial.

This invention will be more particularly described only by way of example with reference to the attached drawings, wherein:

Fig. 1 shows a front elevation of a dial, wherein in the upper portion is shown a fastening type of mounting for the sectors forming the information elements, while in the lower portion a different form of the dial is shown, with the sectors removed;

Fig. 2 shows a partial cross-sectional view of Fig. 1, taken along the line 2—2;

Fig. 3 shows a cross-sectional view similar to that of Fig. 2, of a different form of the invention;

Fig. 4 shows a cross-sectional view similar to that of Fig. 2, of a different embodiment of this invention;

Fig. 5 shows a cross-sectional view taken along the line 5—5 of Fig. 1, with the information element which does not appear in Fig. 1;

Fig. 6 shows a front elevation of a different type of

2

dial, with two series of information elements, concentrically arranged on the dial, the upper part of said figure showing a mounting while an alternative mounting is shown in the lower portion of the same figure, and

5 Fig. 7 shows a cross-sectional view taken along the line 7—7 of Fig. 6.

With reference to the drawings, and particularly to Figs. 1 and 2 which show what can be termed the simplest form of the invention, the dial 10 is embodied by a 10 disc having an annular recess 11 wherein are radially received the sectors 12 carrying the information elements. For clamping said sectors, the recess 11 is provided at its outer edge with a groove 13 undercut in the thickness of the disc, and each sector 12 is provided at both its 15 radially opposite ends, with two projections or shoulders 14 and 15 respectively. The projection 14 is apt to enter the groove 13, while on the projection 15 can bear a ring 16 fastened to the disc 10 by the screws 17. Of course, the several sectors 12 are fastened by the pressure of the ring 16 on the projecting portion 15 and therefore it will be sufficient to loosen the screw 17 in order to allow the slight angular movements of the sectors to bring same to different radial positions, while totally removing the screw 17 and the ring 16 it will be possible 20 to remove all of the several sectors 12.

The arrangement shown in Fig. 4 is substantially corresponding to that shown in Figs. 1 and 2, apart from the fact that the parts are reversed, and particularly the clamping ring 16' has been mounted on the outer edge of 30 the dial which also in this case has been denoted by 10. The sector 12 carrying the information is provided, as in the preceding case, with the step portions 15' and 14', but in this case the part 15' enters a channel totally formed in the body of the disc 10, while on the projection 14' 35 bears, to clamp the sector 12, the ring 16' fixed by the screw 17'.

The Fig. 3 shows the case in which it is expected that the dial is submitted to no shock, vibration or mechanical fatigue; in this case the dial 10 is provided with a recess 40 18 the walls of which are totally smooth, and the sector 19 is provided at its rear portion with a number of permanent magnets 20 which, being the disc 10 made of a suitable material, allow the application by simple magnetical attraction of the various sectors 19 to the disc 10.

45 The lower portion of the Fig. 1 and the Fig. 5 show a different form according to which the disc, denoted also in this case by 10, is provided with arc shaped slots extending through a certain angular extent, and arranged at different radial spacings from the center so as to cover 50 together the entire circumference, denoted at 21. Said slots are made in the bottom of the annular recess 23 of the exposed surface of the dial forming disc 10, and the sectors 22 carrying the information element are provided in their rear surface with an apertured projection, internally threaded, into which may be engaged the screw 55 25 applied from the rear surface to the dial so as to clamp the rear surface of the sector 22 against the facing surface of the recess. Of course, by loosening the screw 25 it will be possible to cause said screw to glide along the 60 associated slot guide 21, and with the screw the sector engaged thereby.

The embodiments as far described have a single information on each radial element of the dial. Figs. 6 and 7 show the case according to which each radial element of the dial is apt to carry two informations which must be capable of being angularly adjusted with respect to each other.

In this case the dial, which is yet denoted by 10, is provided with an annular recess the walls of which are inclined so that the recess is restricted towards the front portion of the dial. This recess is indicated at 26 in 70 Fig. 7. In said recess, two circular concentric series

of sectors 27 and 28, respectively, are arranged, and said sectors are provided with side walls inclined like the sides of the recess 26 so as to be inserted therein by a dovetail connection. In the intermediate circular land which separates the two circular annular units formed by the sectors, is inserted a ring 29 which bears on the facing sides of the sectors 27 and 28, and being provided in its turn with inclined sides complementary to those of the aforesaid sectors, clamps same at their determined positions, being in turn blocked against the dial 10 by means of screws which, as shown at the upper portion of the Figs. 6 and 7, may be either inserted from the front portion of the dial towards its rear surface, or, as shown in the lower portion of said figures, in reverse direction. In said figures, by 30 have been denoted the screws so arranged that their head is exposed on the front surface of the dial, while the numeral reference 31 denotes the screws arranged in contrary direction.

We claim:

1. An indicator dial with adjustable indicia carrying elements, which comprises a disc having a peripheral edge and a central hub, said edge and said hub projecting from the same side surface of the disc and perpendicular with respect to the said surface, said edge and said hub defining between them a cavity in form of an annulus having as a bottom the surface of the said disc, at least one plurality of circular sectors having indicia thereon, said sectors being arranged in the said cavity and abutting at one end against said edge and at the other end against said hub, said sectors being displaceable around said annulus with respect to each other, and means on said disc for fastening said sectors in a desired position with respect to each other and to the disc.

2. An indicator dial as claimed in claim 1, wherein said disc is of magnetic material and each sector is provided in its rear surface facing the bottom of the said cavity with at least one recess, a permanent magnet inserted in said recess and flush with said rear surface, said magnet being in contact with the disc at the bottom of the said cavity to adhere thereto and to fasten the related sector in a desired position with respect to the disc and to the adjacent sectors.

3. An indicator dial as claimed in claim 1, wherein said disc at the bottom of the cavity has a plurality of arc shaped slots there and each of the said sectors has a projection on the surface thereof facing the bottom of the cavity, said projection extending through one of the said plurality of slots, a threaded member screwed onto each of the said projections, said threaded member being in the form of a screw having a head with the diameter greater than the width of the said slots and abutting against the disc to fasten each of the said sectors in a desired position with respect to the disc and to the adjacent sectors.

4. An indicator dial as claimed in claim 1, in which

said disc has a circular recess along the base of the said peripheral edge, and each sector has a step at the two radial ends, the step at the end toward the periphery of the disc extending into the said recess at the base of the said edge, a ring abutting against the said hub and the step portion of each sector at the end toward the center of the disc, threaded members in the form of screws extending through said ring and engageable with the said hub for fastening each sector in a desired position with respect to the disc and the adjacent sectors.

5. An indicator dial as claimed in claim 1 wherein said disc has a circular recess at the base of the said hub and each sector has a step at the two radial ends, the step at the end toward the hub extending into the said recess at the base of the hub, a ring at the periphery of the disc abutting against the edge of the said disc and the step of the sectors at the end toward the periphery of the disc, threaded members in the form of screws extending through the said ring into said edge for fastening each sector in a desired position with respect to the disc and the adjacent sectors.

6. An indicator dial with adjustable indicia carrying elements, which comprises a disc having a peripheral edge and a central hub, said edge and said hub projecting from the same side surface of the disc and perpendicular with respect to the said surface, said edge and said hub defining between them a cavity in form of an annulus having as a bottom the said surface of the disc, the sides of said cavity being inclined toward each other, 30 an annular wall in the middle line of the said cavity having the side surfaces thereof inclined toward said edge and said hub respectively, two pluralities of sectors the first of which lie between said wall and said edge, and the second of which lie between said wall and said hub, 35 the said sectors having arc shaped ends of different lengths and carrying indicia on the sectors, the ends of the said sectors having the walls inclined at the same inclination toward the middle transverse line of the said sectors, the sectors of the said first plurality having the longer 40 ends in engagement with the said edge and the sectors of the said second plurality having the shorter ends in engagement with said hub, the shorter ends of the sectors of the first plurality and the longer ends of the sectors of the said second plurality being engaged with the inclined walls of the said annular wall, and screw means 45 for securing said annular wall to the bottom of the said channel with said sectors of the said first and second pluralities in a desired position with respect to the disc and the adjacent sectors.
